(57) **CLAIM**

The ornamental design for a receptacle for inverted containers, as shown and described.

DESCRIPTION

FIG. 1 is a perspective view of our ornamental design for a receptacle for inverted containers.

FIG. 2 is an alternate perspective view of our ornamental design for a receptacle for inverted containers.

FIG. 3 is a top view of our design shown in FIG. 1.

FIG. 4 is a side plan view of our design shown in FIG. 1.

FIG. 5 is a front view of our design shown in FIG. 1, the back view being identical to the front view; and,

FIG. 6 is a bottom view of our design shown in FIG. 1.

The broken lines in the drawings represent unclaimed environmental subject matter and form no part of the claim.

A receptacle for inverted containers for holding and supporting an inverted container such as a bottle containing a fluid with an applicator tip for dispensing fluid onto a surface. The container with the applicator tip is placed upside down into the receptacle for inverted containers when not being used for dispensing the fluid.
